AMMUNITION CASE

Alfred Dhôme, Paris, France, assignor of one-half to Paul Deffrenne, Paris, France

Application October 2, 1933, Serial No. 691,854
In France October 8, 1932

4 Claims. (Cl. 102—17)

The invention relates to cases for all kinds of sporting ammunition and concerns a new metal case of any metal or metal alloy, of cylindrical or cylindro-conical form at its upper part, terminating in its lower part by a sort of ogive having an axial neck for accommodating the cap. The base or ogival part of the case is surmounted by a cylindrical reinforcement intended to strengthen the case by binding it at the necessary places

5 and to carry a rim for the extraction. In a constructional modification, the body of the case is constituted in the ordinary manner by a cardboard tube, in the lower part of which is suitably engaged a spherical or oval case terminating in a cylindrical neck in which is engaged the cap.

10 Over the cardboard tube is fitted the metal reinforcement which presses it on the spherical or oval case, while engaging the neck of the said case. The accompanying drawing shows in Figure 1 an axial section of an all-metal case according to the invention, and in Figure 2 a similar section of a case made of cardboard and metal.

15 Referring to the drawing, it will be seen that cases shown are sporting cartridge cases. In Figure 1, the actual case is preferably made of steel and, in the construction shown, comprises a cylindrical part 1 extended by a spherical or oval part 2 of lesser length, terminated by a neck 3. This case is produced in a single piece in steel by known processes, and possesses a greater wall thickness in the ogival part which encloses the combustion chamber of the powder, which

20 chamber has to resist considerable stresses. The ogival part 2 is surmounted by a cylindrical reinforcement 4 provided with the usual rim 5. The reinforcement 4 surmounts the case in the region of the union of the ogival part with the cylindrical part and at the place which is subjected to considerable stresses, and is forcibly fitted on the case. This reinforcement which is closed in its lower part, is provided with an opening having inwardly turned edges 6, which opening fits on the neck 3 of the case. It will also be observed that the reinforcement 4 is mounted on a slightly contracted part 2¹ of the ogival part 2 so as to form an internal shoulder 2² intended to serve as abutment for the wad.

25 The case has a variable thickness calculated so as to provide the best conditions of resistance to the stresses developed by the firing of the shot. The profile of the ogival part is likewise calculated to provide the optimum shape for resisting the said stresses. It is likewise calculated to

30 permit the best propagation of the ignited gases of the cap and the integral ignition of all the elements of powder, and to avoid unburnt material.

The cap chamber is reinforced and comprised in the mass of the body, thereby ensuring firmness, irrespective of the number of re-capping operations.

35 The base or reinforcement may be assembled to the case by beading, screwing or by any other method. The body and the base are calculated and treated in such a manner that the base, at the place where it is assembled with the body, that is to say, at one end in the region of the end of the powder chamber, and at the other end in the region of the cap chamber, effects a real binding of its two regions. The powder chamber is thus bound at both ends, thereby increasing its resistance to the stresses to which it is subjected.

40 The case being entirely made of metal and not comprising any part of cardboard, felt or the like, is indeformable, and is entirely protected from the action of moisture.

The danger of the rim being torn off is eliminated, and the rim no longer bears any stress due to the ignition of the powder, since it is completely independent of the body of the case and the powder chamber.

45 The base and the rim are no longer in contact with the gases produced by the cap and the powder, whereby any danger of escape of the gases is eliminated.

The device in question provides for the cap a chamber which forms one piece with the body of the case and is reinforced by the binding of the base. The cap is held perfectly, no escape of gas is possible and re-capping is effected in a perfect manner, since the cap chamber remains intact indefinitely.

50 The powder chamber has a very small diameter at the ogive and cap chamber end. The smallness of this diameter gives it a greater resistance than in the ordinary cartridges where the base has a diameter equal to that corresponding to the calibre of the cartridge.

55 In cardboard cartridges, the tightening effected by the wad on the cardboard body varies according to the strength of the cardboard and the degree of humidity. It is constant, on the contrary, in the device according to the invention, since the body is perfectly rigid in any event.

The form of the combustion chamber gives the optimum result, and the volume of the powder chamber is always constant, since the wad is always stopped at the same place by the internal

shoulder provided on the case. The cases thus provided may be re-charged and re-capped a considerable number of times and practically cannot be worn out.

It is obvious that this construction of cases is applicable to cases for other kinds of ammunition.

In Figure 2, at 1¹ is shown a cardboard tube suitably engaged by one of its ends on the spherical or oval case 2 terminating in a neck 3 in which the cap is placed.

Over the lower end of the tube 1¹ is fitted the cylindrical reinforcement or base 4, which consequently presses the wall of the said tube against the end of the case 2, while at the same time it engages the neck 3 by a cylindrical part 6.

The case 2 constitutes the powder chamber, and the cardboard tube will be employed exclusively to contain the charge of shot. The base 4 ensures the intimate fitting of the cardboard tube 1¹ with the metal case and ensures perfect gas-tightness. Furthermore, the head 4 presses the tube 1¹ on the case 2 at the places which are subjected to maximum fatigue, and the fitting obviates the disadvantages which would result from the variations in diameter and thickness of the cardboard.

The upper end of the chamber formed by the case 2 may be made thinner in order to effect its union with the tube 1¹ and thus to ensure considerable gas-tightness when the pressure of the powder is exerted.

I claim:

1. A cartridge casing comprising a tubular shell including a conoidal base part forming the powder chamber and a cylindrical extension of the base part forming the shot chamber, said base part terminating at its conoidal end in an outwardly projecting nipple adapted to receive a primer for the cartridge and a cylindrical reinforcing element seated on the tubular shell over the conoidal base part, said element having a head provided with an inwardly projecting annular flange seated on the outer part of said nipple.

2. A cartridge casing comprising a tubular shell including a conoidal base part forming the powder chamber and a cylindrical extension of the base part forming the shot chamber, said base part having at its inner part a slightly less cross-area than that of the cylindrical extension, said base part terminating at its conoidal end in an out-

wardly projecting nipple adapted to receive a primer for the cartridge, and a cylindrical reinforcing element seated on the conoidal base part of the tubular shell with the periphery of said element flush with the periphery of the cylindrical extension of the shell, said reinforcing element having a head provided with an inwardly projecting annular flange seated on the outer part of said nipple.

3. A cartridge casing comprising a tubular shell including a conoidal base part forming the powder chamber and a cylindrical extension of the base part forming the shot chamber, said base part terminating at its conoidal end in an outwardly projecting nipple adapted to receive the primer for the cartridge and said base part having its conoidal wall gradually increasing in thickness from its inner edge toward its conoidal end, and a cylindrical reinforcing element seated on the tubular shell over the conoidal base part thereof, said element having a head provided with an inwardly projecting annular flange seated on the outer part of said nipple.

4. A cartridge casing comprising a tubular shell including a conoidal base part forming the powder chamber and a cylindrical extension of the base part forming the shot chamber, the tubular shell having an interior annular shoulder at the junction of the base part with the cylindrical extension to form an abutment for the wad inserted in the shell to separate the powder and shot chambers; said base part terminating at its conoidal end in an outwardly projecting nipple adapted to receive a primer and the inner part of the base part having slightly less cross-area than that of the cylindrical extension, with the conoidal wall of the base part gradually increasing in thickness from the annular shoulder toward its conoidal end; and a cylindrical reinforcing element seated on the casing over the conoidal base part thereof with the periphery of said element flush with the periphery of the cylindrical extension of the casing, the reinforcing element having a head provided with an inwardly projecting annular flange seated on the outer part of said nipple, and the reinforcing element having its cylindrical wall gradually increasing in thickness toward the head of the element.

ALFRED DHÔME.
